ELECTRIC SWITCH.

Application filed May 29, 1926. Serial No. 112,530.

This invention relates to electric switches and is herein shown embodied in a flashlight structure.

An object of the invention is to provide a generally improved switch which is simple in construction, reliable in use, easily assembled, capable of withstanding prolonged use, and particularly adapted for use in a flashlight.

10 The invention will be understood from the following description, taken in connection with the accompanying drawings, in which—

15 Figure 1 is a central vertical section through the switch embodying the invention, the switch being shown in connection with a flashlight.

20 Figure 2 is a horizontal sectional view taken on the line 2—2 of Figure 1, the circuit closing member being shown in its housed position.

25 Figure 3 is a view similar to Figure 2 but showing the circuit closing member in position to be moved into closed circuit position.

Figure 4 is a view similar to Figure 1 but showing the switch unit in elevation.

30 Figure 5 is a vertical sectional view taken on line 5—5 of Figure 3.

Referring to the drawings, the casing 5 of a flashlight with which the switch unit embodying the invention is adapted to be used, is formed with an inwardly projecting bead or seat 6 upon which the switch unit is retained by means hereinafter more fully described. The casing 5 is screw-threaded, as shown at 7, and is adapted to receive any appropriate type of head, not shown.

35 The switch unit is adapted to be assembled exteriorly of and thereafter introduced into the casing 5, within which it is retained with a portion of its operating member 10, of insulating material, and a portion of its base 11, also of insulating material, projecting through an opening 12 formed in the casing 5. The base 11 is provided with a depending boss 13, which serves as a bearing for a pivot 14, by means of which pivot the operating member 10 is pivotally connected to the base 11. The base 11 is also provided with a rivet 15, the bottom end of which is headed over and serves as a contact, adapted to engage the carbon electrode 18 of the usual flashlight battery B, having its zinc electrode 19 suitably connected to the casing 5 in accordance with usual prac-

tice. Associated with the base 11, is a pair of resilient contacts 20 and 21, of which the contact 20 terminates in a resilient finger 22, while the contact 21 terminates in a conductor strip 23. The conductor strip 23 is confined within a pocket 24 formed in the base 11 and is held in position with respect to the base 11 by the rivet 15. The contact 20 is secured in position by means of a rivet 25, passing through the support 11. The upper end or head of the rivet 25 engages that portion of the finger 22 that rests upon the base 11, and is adapted for the reception of one end of a tension spring 30 which is, at its other end, suitably connected to a headed pin 31 carried by a metal insert 32 by which the pivot 14 is carried and around which the insulating material forming part of the operating member 10 is molded.

40 Within the operating member 10, is slidably mounted a circuit closing member 33, which is formed with a grooved head 34, the forward or pointed end 35 of which is adapted to be moved into engagement with the outwardly turned ends 36 of the angularly disposed arms 37 of the contacts 20 and 21, after moving the operating member 10 to its position shown in Fig. 3. Movement of the circuit closing member 33 into engagement with the contacts 20 and 21 is resisted by a compression spring 38, which surrounds the shank portion of the circuit closing member 33 and is confined within a chamber 39 formed in the insert 32. This spring 38, at one end, engages a metallic bearing 40, adapted for a drive fit into one end of the chamber 39 and, at its other end, engages an operating button 41, of insulating material, carried at the outer end of the circuit closing member 33. The spring 38, as will be readily appreciated, acts to normally retain the circuit closing member 33 in its retracted position, but will permit movement of the circuit closing member into engagement with the contacts 20 and 21 when it is desired to operate the flashlight either intermittently or constantly.

45 As above stated, the switch unit is adapted to be assembled exteriorly of and thereafter introduced into the flashlight casing 5. In finally assembling the unit, a suitable housing 47 is connected to the base 11 by means of rivets 48. These rivets 48 are passed through the base 11 and flanges 49 which are formed integral with the housing 47 at the

time of forming the inwardly projecting portions 50 in the inclined wall of the housing 47. This housing serves not only to protect the various cooperative elements entering into the switch unit, but also serves as a support for the flashlight lamp 51, of the usual construction, having central and outer contacts 52 and 53, respectively. The lamp 51 is removably carried within a screw-threaded socket 54, suitably connected with the housing 47 and provided, at its inner end, with a disc 56 of insulating material through which extends a rivet 57, or the like, adapted to engage at one end the resilient finger 22 and at the other end the central contact 52 of the lamp 51.

In order to retain the switch unit properly positioned within the flashlight casing 5, a retaining element 58 is provided, the retaining element being so shaped as to fit the upper end of the housing 47, and being provided at its lower end with a flange 59 which engages a shoulder 60 formed on the housing 47 substantially midway of its length. The periphery of the flange 59 terminates in an upwardly projecting screw-threaded apron or flange 61 which engages the inside of the screw-threaded end 7 of the flashlight, upon which end the flashlight head, not shown, is adapted to be carried, as previously explained. In order to prevent turning of the switch unit as the retaining element 58 is being run down into firm engagement with the housing 47, that portion of the base 11 which projects through the opening 12 is so shaped as to snugly engage inturned flanges 62 which are formed integral with the casing 5 and are arranged at opposite ends of the opening 12.

Assuming that the operating member 10 is positioned as shown in Fig. 2 and that it is desired to intermittently close the flashlight circuit, the operating member 10 is first moved to its position shown in Fig. 3. The circuit closing member 33 may then be so moved against the influence of the spring 38 as to cause the pointed end 35 of the head 34 to touch and electrically connect the ends 36 of the contacts 20 and 21, the spring 38 serving, upon release of pressure from the operating button 41, to return the circuit closing member 33 to its normal position. The lamp may thus be "flashed" by gently pressing and releasing the circuit closing member. However, if it is desired to close the flashlight circuit for any considerable length of time, the circuit closing member 33 is moved against the influence of the spring 38 a sufficient distance to cause the head 34 to pass between the ends 36 of the arms 37, which are flexed by the camming action exerted thereupon by the pointed end 35 of the head. Upon sufficient movement of the circuit closing member 33, the arms 37 of the contacts 20 and 21 spring into the

groove of the head 34, and when so positioned they exert, due to their inherent resiliency, a sufficient grip upon the head 34 to overcome the influence of the spring 38 and retain the circuit closing member 33 in closed circuit position, as shown in Fig. 5. The lamp will then remain lighted regardless of manual pressure on the circuit closing member. When it is desired to release the grip of the contacts 20 and 21 upon the head 34 and thereby open the flashlight circuit, the operating member 10 is rotated from its position shown in Fig. 5, to its position shown in Fig. 2. As a result of such movement the head 34 passes laterally out of engagement with the arms 37, as will be readily appreciated, whereupon the spring 38 acts to return the circuit closing member 33 to its normal position, and the spring 30 serves, after retarding initial movement of the operating member 10, to complete further movement of this member with a quick snap action to its safety position, shown in Fig. 2. Since the tension line of the spring 30 is at one side of the pivotal center of the operating member 10 when such member is in the position shown in Fig. 2, and at the other side of the pivotal center of the operating member when such member is in the positions shown in Figures 3 and 5, the spring 30 affords an effective means for yieldably retaining the operating member in either of such positions, the tension of the spring 30 being sufficient to prevent, under ordinary circumstances, accidental movement of the operating member 10 out of either of its positions of rest. In order to limit the movement of the operating member 10 in both directions, shoulders or stops 64 and 65 are provided, the former being adapted to engage one side of the contacts 20 and 21 when the operating member is positioned as shown in Fig. 2, and the latter being adapted to engage the other side of the contacts 20 and 21 when the operating member is moved to its position, shown in Figs. 3 and 5.

The disk-like member 10 swings on a pivot (14) which is parallel with the axis of the casing 5 and serves as a carrier for the spring-retracted push-button. This push-button is adapted to move in a direction perpendicular to the axis of the carrier in the closing of the circuit. The contact-members 20 and 21 constitute a jack, the space between the members being in a plane perpendicular to the axis of the casing. The segmental peripheral surface 10^a of the push-button carrier projects sufficiently to serve as a thumb-piece. The periphery of the carrier is recessed at 10^b to accommodate the thumb in working the push-button.

The foregoing detailed description has been given for clearness of understanding only, and no unnecessary limitations should be understood therefrom, but the appended

claims should be construed as broadly as permissible, in view of the prior art.

Having thus described the invention what is claimed is:

5. 1. In a switch, a support, a movable operating member associated with said support, means for resisting initial movement of said operating member and for thereafter facilitating further movement of said operating member, a movable circuit closing member associated with said operating member, and yieldable means resisting movement of said circuit closing member in one direction and facilitating movement of said circuit closing member in an opposite direction.
10. 2. In a switch, a support, a movable operating member associated with said support, a movable circuit closing member associated with said operating member, yieldable means resisting movement of said circuit closing member to closed circuit position and tending to move said circuit closing member out of closed circuit position, and a pair of contacts with which said circuit closing member is adapted to cooperate, at least one of said contacts being adapted to so cooperate with said circuit closing member as to retain the same in closed circuit position against the influence of said yieldable means.
15. 3. A switch comprising a support, a movable operating member associated with said support, a movable circuit closing member associated with said operating member and adapted to be moved from open circuit position to closed circuit position, yieldable means resisting movement of said circuit closing member to closed circuit position and tending to move said circuit closing member out of closed circuit position, and a pair of contacts adapted to be engaged by and to interlock with said circuit closing member to retain the same in closed circuit position.
20. 4. A switch comprising a support, an operating member pivotally mounted upon said support and adapted to be moved in opposite directions, means retarding initial movement and thereafter effecting a snap movement of said operating member, a pair of contacts, a circuit closing member carried by said operating member and adapted to be moved bodily with said operating member into a position to be thereafter moved into engagement with said contacts.
25. 5. A switch comprising a support, an operating member pivotally mounted upon said support and adapted to be moved in opposite directions, means retarding initial movement and thereafter effecting a snap movement of said operating member, a pair of contacts, a circuit closing member carried by said operating member and adapted to be moved bodily with said operating member into a position to be thereafter moved into engagement with said contacts, said contacts and said operating member being constructed for interlocking engagement whereby said circuit closing member may be temporarily retained in closed circuit position.
30. 6. A switch comprising a support, an operating member pivotally connected to said support, a pair of contacts associated with said support, a circuit closing member slidably carried by said operating member and adapted to be moved bodily upon movement of said operating member in one direction into a position to be moved into engagement with said contacts, and means associated with said circuit closing member and adapted to cooperate with said contacts for temporarily locking said circuit closing member in closed circuit position, said means being adapted to sever its cooperation with said contacts upon reverse movement of said operating member.
35. 7. A switch comprising a support, an operating member pivotally connected to said support, a pair of contacts associated with said support, a circuit closing member slidably carried by said operating member and adapted to be moved bodily upon movement of said operating member in one direction into a position to be moved into engagement with said contacts, and means associated with said circuit closing member and adapted to cooperate with said contacts for temporarily locking said circuit closing member in closed circuit position, said means being adapted to sever its cooperation with said contacts upon reverse movement of said operating member, and a lamp supporting housing carried by said support and enclosing said operating member, circuit closing member, and said contacts.
40. 8. In combination, a casing having an opening therein, a movable operating member having a portion projecting through said opening, and a circuit closing member movable with said operating member into and out of alignment with said opening.
45. 9. In combination, a casing having an opening therein, a support in said casing, an operating member pivoted to said support and having a portion projecting through said opening, and a circuit closing member movable with respect to said operating member and movable with said operating member into and out of alignment with said opening.
50. 10. In combination, a casing having an opening therein, a support in said casing, an operating member pivoted to said support and having a portion projecting through said opening, and a circuit closing member slidably carried by said operating member and movable with said operating member into and out of alignment with said opening.

11. In combination, a casing-member having a lateral opening, a support in said casing equipped with a jack and with contacts above and below said support electrically connected with the members of said jack, a carrier mounted on said support and adapted to oscillate in a plane transverse with respect to the axis of said casing-member, said carrier having a thumb-piece presented at said opening, and a circuit-closer mounted on said carrier and adapted to close the circuit between the members of said jack. 60
12. In combination, a casing-member having a lateral opening, and a switch-unit insertable through the end of said casing-member, said switch-unit comprising a supporting member equipped with switch-contacts and equipped also at opposite sides with terminal contacts electrically connected with said switch-contacts, a carrier pivotally mounted on said support and having a thumb-piece presented at said slot, and a spring-retracted circuit-closer mounted on said carrier. 65
13. In combination, a casing-member having a lateral opening, and a switch-unit insertable through the end of said casing-member, said unit comprising a support equipped with switch-contacts and with terminal contacts electrically connected with the switch-contacts, a carrier pivotally mounted on said support and having a thumb-piece protruding at said opening, and a spring-retracted push-button mounted on said carrier and adapted to be carried into alignment with the space between said switch-contacts by swinging said carrier. 70
14. In combination, a casing-member having a lateral opening and a switch-unit insertable through the end of said casing-member, said unit comprising an insulation-block equipped with a switch-jack and equipped at opposite sides with terminal contacts electrically connected with the members of said switch-jack, a carrier mounted on said block to oscillate about an axis parallel with the axis of said casing-member, and a spring-retracted plunger-like circuit-closer mounted on said carrier and having a contact-head adapted to make flashing contact and also interlocking contact with the members of said switch-jack. 75
15. In combination, a casing-member provided with a threaded extremity and back of said threaded extremity with a lateral opening; a switch-unit comprising an insulation-block equipped with a switch-jack and equipped also at opposite sides with terminal contacts electrically connected with the members of said switch-jack, a carrier pivotally mounted on said block and having a thumb-piece presented at said opening and a spring-retracted circuit-closer mounted on said carrier and co-acting with said switch-jack, a housing-member connected with and projecting from the outer side of said block; a cap-piece having threaded connection with said casing-member and enclosing said housing; and a lamp-socket adapted to receive a lamp inserted through said cap-piece. 80
16. In combination, a casing provided near its end with a lateral opening and provided back of said opening with a seat; a switch-unit comprising an insulation-block supported on said seat and equipped at one side of the axis of the casing with spaced switch-contacts, one of said switch-contacts having connected therewith a terminal contact leading to a lamp and the other switch-contact having connected therewith a terminal adapted to engage the central terminal of a dry-cell, a carrier pivotally mounted on said block opposite the switch-contacts and having a thumb-piece protruding at said opening, a spring-retracted push-button mounted on said carrier and provided with a head adapted to interlock with said switch-contacts, a spring connecting said carrier and block and adapted to hold the carrier yieldingly in the operative and inoperative positions, a housing-member mounted on said block, and housing the spring, the switch-contacts, and the carrier; and means for securing said switch-unit in position in said casing. 85
17. A switch-unit for the purpose set forth, comprising an insulation-block equipped near one peripheral portion with a pair of switch-contacts and equipped at opposite sides with terminal contacts connected with said switch-contacts, a carrier-disk pivotally mounted on said block opposite said switch-contacts, a spring-retracted circuit-closing plunger mounted in said carrier-disk transversely with respect to the axis of said carrier-disk, a spring adapted to yieldingly hold said carrier-disk in a given position, and a housing-member carried by said block and equipped with a lamp-socket. 90
- In testimony whereof, I have affixed my signature to this specification.
